[57] **ABSTRACT**

A method for ventilation within a room, in which a duct is provided in the ceiling of a closed room and another duct is provided under the floor thereof, both passing horizontally through the building, having openings in the same direction and connected with the room by an air supply and an air exhaust pipe, wherein air is supplied through the duct provided under the floor and is exhausted by way of the duct provided in the ceiling.

METHOD FOR VENTILATION WITHIN A ROOM**SUMMARY OF THE INVENTION**

This invention relates to a ventilation system within a closed room, which works most effectively when applied to rooms of a high-storied building.

Ventilation in the prior art in multi-storied buildings has been maintained with common air supply and exhaust duct systems. As the number of floors increases the enlarging of ducts is required accordingly which may suppress the dwelling occupancy of the building and at the same time large apparatus for air supply and exhaust have been made necessary.

The first object of the present invention proposed for alleviating such defects in the prior art is to control the size of air supply and exhaust duct so that the usable volume will not be unduly limited.

A second object of the present invention is to control the use of air supply and exhaust apparatus to the last extent or not to use them.

A third object of the present invention is to provide a system which is not influenced by wind pressure.

BRIEF EXPLANATION OF THE DRAWINGS

The FIGURE shows an embodiment of the present invention, in which a duct in the ceiling and another under the floor of a closed room, both passing horizontally through the building, are provided.

DETAILED DESCRIPTION OF THE INVENTION

The present invention relates to a ventilating system within a room, within a high-storied building, in which an air supply duct is provided under the floor of the closed room and an air exhaust duct is provided in the ceiling thereof, both passing horizontally through the building and connected with the room by an air supply pipe and an air exhaust pipe, by which ventilation in the room is to be maintained. The embodiments of the present invention will be explained in detail below. The FIGURE shows an embodiment of the present invention, wherein the air supply duct 3 is provided under the floor of the closed room 2 in the building 1, passing through it and the air exhaust duct 4 is provided in the ceiling of the room 2 passing through the building in the same direction as the air supply duct 3. The size of the ducts is the same.

The air supply pipe 5 connects the air supply duct 3 with the closed room 2, and the air exhaust pipe 6 connects the air exhaust duct 4 with the room 2. If necessary, a fan may be attached in the air exhaust duct 4 or in the air exhaust pipe 6.

A - A' show the openings of the air supply duct 3, and B - B' the openings of the air exhaust duct 4.

According to the present invention, the inside of the closed room 2 is turned into a neutral zone as the air supply duct under the floor and the air exhaust duct in the ceiling of the room 2 are provided.

When ascending air currents are generated in the closed room 2, the air is exhausted from the air exhaust duct 4 by way of the air exhaust pipe 6 outside of the building 7. Then air which may be equal in quantity to the exhausted air can be supplied from the air supply duct 3 by way of the air supply pipe 5 into the closed room 2. Natural ventilation is performed as mentioned above, but when it is not sufficient, a fan may be

placed in the air exhaust duct 4 in order to accelerate ventilation within the room.

When the building is influenced by wind pressure from the direction of the arrow in FIG. 1, the wind pressure passes by the duct 3 and the air exhaust duct 4, so that it is exhausted to A - A' and B - B'. The inside of the closed room 2 is thus isolated from the efforts of wind pressure.

Embodiment 2

This embodiment is shown in FIG. 2, in which the air exhaust pipe 6 and the air exhaust duct 4 are constructed in the same way as in the embodiment 1, but the air supply duct 3 is transformed. That is, the air supply duct 3 is not constructed independently and only the open parts A - A' of the duct are constructed on the outside wall at the lower part of the room 2. The open parts B - B' correspond to the open parts A - A'.

In this embodiment, natural ventilation makes the air be exhausted from the air exhaust duct 4 into the outside of the room by way of the air exhaust pipe 6, and the air equal in quantity to the said comes into the room 2 from the open parts A - A'.

When wind pressure is given from the direction of the arrow, the air comes into the room 2 from the open part A and the air coming into from the open part B of the air exhaust duct 4 is exhausted from B to B'. So, the same air in quantity as the air coming from the open part A is supplied in the room 2 and exhausted from the open part B into the outside of the building 1 with the air passing by through the air exhaust duct 4.

In this way natural ventilation within the room is to be maintained, and a fan may be attached in the air exhaust pipe 6 or in the air exhaust duct 4 in order to accelerate ventilation forcibly if necessary.

In the present invention described above, the air supply duct 3 and the air exhaust duct 4 are constructed in every room of each floor or on one floor for common use, by which ventilation is performed. Therefore, common ducts covering the whole rooms of the building as in the prior art become unnecessary. So, the present invention is excellent in the fact that the dwelling occupancy may not be suppressed since in this invention the ceiling and the under floor of the room are used.

Next, as common ducts are not necessary, large apparatus for air supply and exhaust may be unnecessary, too. In addition, no wind pressure gives influence because the air supply duct 3 and the air exhaust duct 4 pass horizontally through the building 1.

The claims defining the invention are as follows.

I claim:

1. A system for providing ventilation within a closed room in a building, comprising:

an air supply duct located beneath the floor of said closed room in a horizontal plane and extending completely through said building and communicating with the surrounding atmosphere;

an air exhaust duct located in the ceiling of said closed room in a vertical plane defined by said air supply duct and parallel to said air supply duct and extending completely through said building and communicating with the surrounding atmosphere;

an air supply pipe connecting said closed room to said air supply duct; and

an air exhaust pipe connecting said closed room to
said air exhaust duct,
whereby said closed room is ventilated by fresh air
from outside being provided to said closed room
through said air supply duct and air supply pipe and
stale air is exhausted from said closed room to said
surrounding environment through said air exhaust

duct and said air exhaust pipe and the ventilating
system is independent of wind gusts due to the
aforesaid indirect transfer of air which arrange-
ment of pipes creates natural ascending air cur-
rents within said room.
